CLAIM

The ornamental design for a hand-held shower head with face plate, as shown and described.

DESCRIPTION

FIG. 1 is a front perspective view of a hand-held shower head with face plate showing our new design;

FIG. 2 is a front elevational view thereof;

FIG. 3 is a left side elevational view thereof, with the right side elevational view being a mirror image;

FIG. 4 is a top plan view thereof;

FIG. 5 is a bottom plan view thereof;

FIG. 6 is a rear elevational view thereof;

FIG. 7 is a front perspective view of an alternative embodiment of the handle-held shower with face plate showing our new design;

FIG. 8 is a front elevational view thereof;

FIG. 9 is a left side elevational view thereof, with the right side elevational view being a mirror image;

FIG. 10 is a top plan view thereof;

FIG. 11 is a bottom plan view thereof; and,

FIG. 12 back elevational view thereof.
